[57] CLAIM

The ornamental design for a seat, as shown and described.

DESCRIPTION

FIG. 1 is a front perspective view of a seat in the form of a sofa showing my design;

FIG. 2 is a front elevational view;

FIG. 3 is a side elevational view, the opposite side a mirror image thereof; and

FIG. 4 is a front elevational view of a second embodiment of the seat in the form of a chair.

The rear view is substantially unornamented.

FIG. 4
